OF MILWAUKEE, WISCONSIN, A CORPORATION OF WISCONSIN

MOISTENER

Application filed November 17, 1926. Serial No. 148,780.

This invention relates to an improved moistener especially designed for use in moistening yarn or silk thread as it is being fed in a knitting machine to be knit into a fabric.

5 One of the principal objects of the present invention is to provide a moistener which is of simple and durable construction, which is comparatively inexpensive to manufacture, which may be easily installed in the conventional knitting machines, and which involves no moving parts liable to be gummed up with lint or otherwise.

Another important object of the invention is to provide a moistener which properly and 15 effectively applies the liquid, preferably a light specially prepared oil, to the yarn or silk thread without wearing the thread and without wearing or otherwise impairing the means employed to effect the application of 20 the oil to the thread.

Another object is to provide means for regulating and controlling the supply of oil to the oil applying means whereby a proper and uniform amount of oil is applied to the 25 thread at all times.

Other objects and advantages reside in certain novel features of the construction, arrangement and combination of parts which will be hereinafter more fully described and 30 particularly pointed out in the appended claims, reference being had to the accompanying drawings forming a part of this specification, and in which:

Figure 1 is a fragmentary view in side 35 elevation showing a moistener for thread embodying the present invention;

Fig. 2 is a plan view of the moistener with the jar or container for the liquid removed from the reservoir;

40 Fig. 3 is a fragmentary sectional view on lines 3—3 of Fig. 2 and showing a section of the jar or container in position on the adjustable platform;

Fig. 4 is a detail perspective view of the 45 body of the liquid applying means;

Fig. 5 is a detail view in elevation of the wick embodied in the liquid applying means; and

Fig. 6 is a detail perspective view of the 50 throttle plate employed for regulating the

flow of liquid from the reservoir to the liquid applying means.

In carrying out the present invention a reservoir 1 is provided and has the form of a cylinder open at its upper end and closed at its lower end by a sloping bottom 2. In the center of the bottom 2 a threaded bearing 3 is provided. Fitted into the bearing 3 is a screw 4 which has an operating knob 5 at its lower end and a platform 6 at its upper end. The platform 6 is spaced a short distance from the bottom 2 of the reservoir and may be raised or lowered by the screw 4. A packing gland 7 is provided for the bearing 3 and screw 4 to prevent leakage of liquid therethrough. A stop pin 5a coacts with the knob 5 to limit the upward movement of the platform 6. On the platform 6 the container for the liquid is mounted. The liquid in the present instance is a light, specially prepared oil. Preferably, the container comprises a jar 8 which is inverted and has its cap 9 resting on the platform 6. The connection between the cap 9 and the neck of the jar is sealed by a gasket 10. In the cap a discharge opening 11 is provided. This arrangement provides means for maintaining a constant level of the liquid in the reservoir 1. By turning the screw 4 and raising and lowering the platform 6, the jar 8 is raised and lowered and the level of the liquid in the reservoir 1 may be raised and lowered.

As shown to advantage in Fig. 3 the reservoir 1 has an outlet 12 in its body portion and this outlet leads to the liquid applying means which comprises a body 13, preferably in the form of a block of metal. The body 13 is supported on a bracket 14 secured by a screw 15 to the reservoir 1. The body 13 being in the form of a block of metal is hard and rigid and substantially non-wearing. Across its top face the block 13 is provided with a groove 16 through which the thread T is guided and freely passes. This groove 16 is intersected by a wick receiving opening 17 extending vertically downwardly through the block 13 from the upper face of the block to a point midway the top and bottom of the block. The lower end of this wick receiving opening 17 communicates with an intake 100

opening 18 which leads out through the inner face of the block 13 and is substantially aligned with the outlet 12 of the reservoir 1. Between the block 13 and the reservoir 1 a throttle plate 19 is interposed, the throttle plate 19 having a minute or restricted port 20 which affords communication between the intake opening 18 and the outlet 12 of the reservoir but which so retards the flow of liquid as to permit only the proper quantity to pass from the reservoir to the wick to be later described. These throttle plates 19 are provided in sets or series and the plates of the sets or series have openings of different size so that by changing the throttle plates 19 the flow may be decreased or increased as desired. To provide for the desired seal between the reservoir and the throttle plate and the throttle plate and the block 13, the plate 19 may be shellacked or otherwise packed or sealed so that when the block 13 is forced up against the plate 19 and the plate 19 is forced up against the reservoir by the clamping screw 21 provided for this purpose, a liquid-tight union will be maintained between these parts. As shown in the drawing, the screw 21 is threaded through the bracket 14 and bears against the block 13.

For the purpose of insuring flow through the restricted port 20 of the throttle plate 19, a vent opening 22 is drilled through the block 13 and leads from the upper face of the block to the intake opening 18.

A wick 25 is fitted in the wick receiving opening 17 and extends down to the bottom of this opening 17 and up to the top thereon. The upper portion of the wick 25 is formed with a slot 26 which is aligned with the groove 16 of the body 13 and is designed to permit of the free passage of the thread T therethrough. The slot 26 of the wick is of such size with respect to the thread T that the film F of oil or liquid that is maintained on the walls of the slot 26 of the wick always engages and contacts with the thread T. Thus, as the thread passes through the slot 26 it is wiped by this film of oil and in this manner the oil is properly applied and distributed on the thread.

The thread T is passed through guides 30 and 31 carried on arms 32 and 33 provided on the reservoir so as to be constrained to pass through the groove 16 of the body of the liquid applicating means. Preferably, a tensioning device 35 is provided for the thread between the guide 30 and the body 13 of the liquid applicating means, the tensioning device comprising loose disks 37 freely rotatable on a fixed tension shaft 38 and urged toward each other by a compression spring 39, the tension of which is varied by an adjustable abutment 40 in the form of a nut threaded on a reduced extension of the shaft 38. A guard 41 in the form of a wire extends around the

tensioning device between the guide 30 and the bracket 14.

The moistener is supported on a standard 50 carried by a stationary part of the machine on the frame thereof by means of a clamp 51 carried by the reservoir 1 and cooperating with the standard 50.

With this moistener the thread does not wear away the wick and is not itself worn by severe wiping contact with a liquid applicating element. On the contrary, the thread is thoroughly and effectively moistened by the film of oil which is maintained on the walls of the slot of the wick and the thread is constrained to pass properly through the slot of the wick by the action of the guard slot in the hard and rigid body 13 of the liquid applicating means. The wick 17 is maintained properly saturated with the oil or liquid by virtue of the feature of having a properly controlled flow of the oil or liquid to the wick at all times. This controlled flow is regulated or governed by the size of the port in the throttle plate and by the level of the liquid in the reservoir. As pointed out, a throttle plate having the desirable size of port therein is used and the level in the reservoir may be varied by turning the screw 4. Usually a variation in the level of the liquid in the reservoir is sufficient to properly control the flow, but where this does not serve, then a different throttle plate must be used.

The invention claimed is:

1. A moistener for thread comprising a reservoir having an outlet, liquid applicating means associated with the outlet of the reservoir, and means for regulating the flow of liquid from the reservoir to the applicating means and including a throttle element having a minute port therein through which the liquid is constrained to flow, said port being sufficiently minute to provide for proper flow.

2. A moistener for thread comprising a reservoir having an outlet, liquid applicating means including a body having an intake opening adjacent and aligned with the outlet, and a throttle plate interposed between the outlet and the intake opening and having a small port therein permitting proper and uniform flow from the outlet to the intake opening, said body having a vent for the intake opening.

3. A moistener for thread comprising a reservoir having an outlet, liquid applicating means comprising a hard and rigid body provided with a thread receiving groove across one face and having a wick receiving opening intersecting the groove and an intake opening communicating with the wick receiving opening, a throttle plate interposed between the body and the reservoir, means for clamping the body against the throttle plate and the throttle plate against the reservoir, said throttle plate having a re-

5 stricted port provided for the uniform flow of the proper amount of liquid to the intake opening from the reservoir, and a wick in said wick receiving opening having a slot through which the thread is passed, the slot of the wick being alined with the groove of the body.

10 4. A moistener for thread comprising a reservoir having an outlet, liquid applicating means comprising a hard and rigid body provided with a thread receiving groove across one face and having a wick receiving opening intersecting the groove and an intake opening communicating with the wick 15 receiving opening, a throttle plate interposed between the body and the reservoir, means for clamping the body against the throttle plate and the throttle plate against the reservoir, said throttle plate having a restricted port provided for the uniform flow of the proper amount of liquid to the intake opening from the reservoir, and a wick in said wick receiving opening having a slot through which the thread 20 is passed, the slot of the wick being alined with the groove of the body, and means for maintaining a constant level of liquid in the reservoir.

25 5. A moistener for thread including liquid applicating means, consisting of a wick adapted to present a film of liquid to the thread for moistening the same and a body substantially enclosing the wick and supporting the same in a fixed position and having 30 means for constraining the thread to contact only with the film of liquid.

35 6. A moistener for thread including liquid applicating means comprising a wick having a slot through which the thread passes, and 40 means supplying liquid to the wick to maintain films of liquid on the walls of the slot, the slot being of such size in relation to the thread that only the films of liquid on the walls of the slot contact with the thread to 45 moisten the same.

50 7. A moistener for threads including liquid applicating means comprising a body provided with a thread receiving groove across one face and also having a wick receiving opening intersecting said groove, a wick fixedly supported in said opening and having a slot registering with the groove of 55 said body and through which the thread passes and means for supplying liquid to the wick to maintain films of liquid on the walls of the slot, the slot being of such size in relation to the thread that only the films of liquid contact with the thread to moisten the same.

60 8. A moistener for threads including a wick having a slot through which the thread passes, means for constraining the thread to move properly through the slot without having wearing contact with the wick, and 65 means for supplying the wick with liquid.

9. A moistener for thread comprising a reservoir having an outlet, liquid applicating means associated with the outlet of the reservoir, and means for regulating the flow of liquid from the reservoir to the applicating means and including a throttle element having a minute port therein through which the liquid is constrained to flow, said port being sufficiently minute to provide for proper flow, and means for raising and lowering the level of the liquid in the reservoir and constantly maintaining it at the selected level.

70 75 In witness whereof, I hereto affix my signature.

80 HENRY HELLWEG.
